(57) CLAIM

The ornamental design for a wearable flag having a hood and a pouch for storing the hood, as shown and described.

DESCRIPTION

FIG. 1 is a perspective view of a wearable flag having a hood and a pouch for storing the hood, according to our design, shown in use with environmental subject matter of an exemplary user opening his/her arms wearing a hood portion over his/her head and a flag portion with an attached pouch portion in an open state over his/her back by inserting his/her fingers through a pair of loops included at two corners of the flag portion, respectively.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a perspective view of a wearable flag having a hood and a pouch for storing the hood, according to our design, shown in use with environmental subject matter of an exemplary user opening his/her arms wearing a flag portion with an attached pouch portion in a closed state containing a hood portion folded and stored therein over his/her back by inserting his/her fingers through a pair of loops included at two corners of the flag portion, respectively.

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

The short evenly broken lines are shown for the purpose of illustrating environmental subject matter of an exemplary user and exemplary patterns, none of which form part of the claim. The longer evenly broken lines represent exemplary stitches and form no part of the claim.
